FRIEDRICH MUNZINGER, OF BERLIN-WILMERSDORF, GERMANY.

METHOD AND MEANS FOR CONTROLLING THE WATER LEVEL IN STEAM BOILERS.

Application filed June 19, 1923. Serial No. 646,431.

To all whom it may concern:

Be it known that I, FREIDRICH MÜNZINGER, a citizen of the German Realm, residing at Berlin-Wilmersdorf, Kaiserallee 30, have invented certain new and useful Improvements in Methods and Means for Controlling the Water Level in Steam Boilers, of which the following is a specification.

The present invention relates to a method of and apparatus for controlling the water level in steam boilers. The control of the supply of feed water in steam boilers is effected, almost without exception, by maintaining a water level as constant as possible, whatever the load of the boiler and the steam pressure of the same may be. It is evident, however, that such a control is only desirable as long as the working conditions are approximately constant, whereas, in case of steam boiler plants of highly varying loads, the control of the supply of feed water effected in the manner above described calls for great adaptability as regards the supply of heat to the boilers, that is, said control requires that, on a sudden increase in the consumption of steam, the supply of heat to the boiler shall increase correspondingly, and vice versa. Otherwise undesirably great variations of pressure will occur. When the steam consumption suddenly increases, the pressure begins to fall. At the same time, however, with the usual automatic control, an increased supply of feed water to the boiler also takes place, in order to impede the falling of the water level. This will be so even though a correspondingly increased supply of fuel takes place simultaneously since the effect of increased firing on the production of steam is not felt immediately but some time after the increase in firing. Furthermore when the steam consumption suddenly decreases the development of heat cannot be varied simultaneously at a corresponding rate, and an undesired increase of pressure and blowing of the safety valves etc. occurs.

The present invention has for its object to provide a method of and apparatus for control which permits these drawbacks to be avoided or moderated in a high degree. According to the invention, the water level is not adjusted, as before, to a height as constant as possible, but to a height which is variable within certain limits, the water level, being automatically raised, when the

pressure of the boiler increases, and lowered on a falling pressure of the same.

Consequently, if the load of the boiler is suddenly increased, the water level determining the control is automatically lowered, and the increased feeding, which would otherwise take place, and the still greater decrease of the pressure of the boiler due thereto are prevented. On the supply of heat being gradually increased, a gradual increase of the pressure of the boiler is effected, and at the same time a gradual rising of the water level takes place, that is, on an increased supply of heat, the boiler will be gradually fed until the initial conditions are restored. Conditions will be reversed on a sudden decrease of the load.

The method according to the invention may also be carried out in such a way that, prior to great variations of load which may be expected to occur at given moments, the supply of heat is correspondingly increased or decreased. In conformity with the increase or decrease of static pressure in the boiler thus occurring, the water level to be adjusted is at the same time raised or lowered. Thus, for instance, if from experience the steam consumption will fall to half of its value at a given moment (noon rest), and the boiler consequently requires only about the half of its normal supply of heat during said period, this undesired irregularity of the supply of heat may be moderated by lowering the supply of heat to about $\frac{3}{4}$ at a short time prior to said decrease of the load. As then the formation of steam is not at first sufficient for the demand, the pressure of the boiler will fall and the water level to be adjusted will be accordingly gradually lowered, until a state of constancy is reached. As soon as the lower steam consumption will then set in, the formation of steam preponderates over the demand, thus causing a gradual return to the initial operating condition. In such a way, too sudden an increase of pressure and blowing of the safety valves during the time in which the supply of heat preponderates over the steam demand, is avoided, without it being necessary to vary the supply of heat suddenly and forcibly.

A more or less effective influence due to the variations of the boiler pressure will be effected depending on the construction of the controlling device. An especially effective

- action will be obtained, if, at normal pressure the feed is controlled solely in response to variations in water level and, when the boiler pressure differs from the normal value, the action of the water level upon the supply of feed water is nullified and the feed is controlled solely in response to static pressure in the boiler, said supply being increased on the pressure rising, and decreased 5 on the pressure falling, until the water level reaches a maximum or minimum value at a certain distance from the upper or lower allowable limit, and then the influence of the boiler pressure is nullified and the supply of feed water is again made dependent solely 10 on the variation of the water level.

The control should preferably be carried out so that the boiler pressure will not be effective at every small difference from the normal pressure, and consequently, the method is preferably carried out so that the supply of feed water is not affected by the boiler pressure before said pressure differs 20 from the normal boiler pressure by a certain minimum amount, said supply being adjusted within these limits entirely in conformity with the water level, as usual.

The course of the method of regulation is then, preferably, as follows: The normal boiler pressure is supposed to be 15 atmospheres. The arrangement may be such that, for example, between 14.7 and 15.3 at., the pressure has no influence on the feeding. Within these limits, said supply will consequently be adjusted in conformity with the water level prevailing as usual. If, however, the pressure falls for instance to 14.69 at., the supply of feed water is decreased, and, at about 14.4 at., cut off entirely, whatever the height of the water in the boiler may be. Accordingly, the supply member will open more at pressures above 15.3 at., said member being fully opened at about 15.6 at., whatever the water level was before. These limits of pressure may of course be kept narrower or wider, if desired.

As long as the pressure is lower than 14.7 at. and higher than 15.3 the water level will first fall or rise continuously, causing a great counteraction upon the pressure. According to circumstances, the variation of pressure may by this means be brought into rest, or may even be reversed, so that under circumstances the boiler pressure will again reach the range, within which the feeding is only operated by the water level. If, however, the deviation of the boiler pressure beyond the given amount lasts for any longer period, the water level will remain on the fall or on the rise. As soon as the level has reached the allowable upper or lower limit save for a short distance therefrom, the influence of the boiler pressure will again be nullified, so that, within these two safety distances, the supply of feed water is operated entirely by

the water level itself. On the level again approaching the lower limit, the supply of feed water is again started, or on the level approaching the upper limit it is again decreased in such a way that, under all circumstances, the water level is prevented from falling or rising beyond the given limits. 70

The advantage of the method of regulation above described is that, on temporary variations of load, a considerable moderation of 75 the variations of pressure thus occurring may be obtained and, moreover, that on variations of load of a longer duration, a great period of time will be available for the adjustment of the supply of heat according to 80 the modified conditions, within which period no undesired variations of pressure will occur.

The invention will be more fully described with reference to the accompanying drawings, in which, Fig 1 shows one modification of apparatus for carrying out my invention having a plurality of feed valves, only so much of a boiler being shown as is necessary to properly disclose the invention; Fig. 2 85 shows a second embodiment wherein a single valve is used; Fig. 3 shows a third embodiment showing a different means of interconnecting the water level and pressure responsive devices; Fig. 4 shows a fourth embodiment wherein an electric regulator is used; Fig. 5 shows a cross section of a boiler drum embodying a fifth form of the invention; Fig. 6 shows a longitudinal view of the boiler drum of Fig. 5; Fig. 7 shows a sixth 90 embodiment wherein the pressure responsive device places an additional load on the water level responsive device; and Fig. 8 shows, diagrammatically the preferred manner of 95 using my novel feed water regulator in conjunction with a battery of boilers.

In Fig. 1, *a* is the upper drum of a steam boiler. As long as equilibrium prevails between the quantity of water supplied and the quantity of water evaporated, the steam pressure being approximately equal to the normal, which is again, for sake of illustration assumed to be 15 at., the water level is maintained within narrow limits, for instance between *f* and *g*, by the float *b* which operates the feed water valve *e* inserted in feed conduit 20 by means of the rod *c* and the lever *d*. The arrangement is such that no water is supplied to the boiler at a position of the regulating valve *e* corresponding to the level *f*, whereas a quantity of water equal to the maximum steam output of the boiler is supplied at a position of the valve *e* corresponding to the level *g*. A motor responsive to static pressure in the boiler preferably in the form of a piston *h* modifies the action of the float as herein set forth. On a normal steam pressure the piston *h* in the cylinder *j*, the one side of which is operated 10 by the static steam pressure in the boiler 11

through conduit *w* while the other side is subjected to the action of a spring *v*, is in its middle position, this being also the case with the piston rod *i* fixed on the piston. Between the two stops *k* and *l* of the rod *i* the lever *d* of the valve *e* may play freely on variations occurring in the water level. Now, if the load varies without the supply of heat being simultaneously varied, the pressure of the boiler will increase or decrease, and the piston will move somewhat downwards or upwards without, to begin with, the supply of feed water being altered. If, however, the pressure falls below or rises above the normal value by a certain amount, say 0.3 at., one of the two stops *k* or *l* will engage the lever *d* which will then be correspondingly displaced, the valve *e* being gradually closed on a further fall in the pressure, and gradually opened on a further rise in the pressure. The water level will fall or rise correspondingly.

Now, if the fireman does not use more coal in spite of the boiler pressure falling considerably, the water level will tend gradually to fall below a minimum permissible value, thus jeopardizing the boiler. A second float *m* then operates a second valve *o* connected in parallel to the first regulating valve *e* in such a manner that, when the water level has fallen to the height *p*, said second valve will open and prevent a further falling of the water level.

On the other hand it may occur on a decreasing load that the water level tends to rise above a maximum permissible value *q*, because of the regulator keeping the valve *e* opened. A third float *n* then operates a cut-off member *r* inserted behind the valve *e* and shuts off further supply of feed water, whatever the boiler pressure may be.

If, on a variation of the load, the fireman increases or decreases the supply of coal according to the prevailing steam consumption, the different valves will operate automatically in such a way that after some time the valve *o* will be fully reclosed, or the valve *w* will be fully re-opened, while the regulator *h* will be put out of engagement with the lever *d* and the water level will again adjust itself between the limits *f* and *g*.

In Fig. 2, the floats *b*, *m* and *n*, instead of actuating the three valves *e*, *o* and *r*, operate on a single valve *e*. The operation of float *b* and the pressure responsive motor is the same as in the modification of Fig. 1, the operation being modified by the action of floats *m* and *n* as follows. If the water level rises beyond the value *q*, the float *n* shuts off the steam from the upper side of the piston *h* by means of the valve *s* and connects the same with the atmosphere through opening 30, thus causing the valve *e* to be closed. If the water level falls below the value *p*, float

m is lowered thereby opening valve *t* in conduit 17 and allowing steam pressure to act on the area 18 on the extension 19 of the piston *h*, which, in this figure is shown as a differential piston. This added pressure is sufficient to overcome the spring *v* and open valve *e* regardless of the tendency of decreased pressure acting through conduit *w* to hold the valve closed. 70

In Fig. 3, the float *b* of the automatic feed regulator actuates the supply valve *e* in the feed water supply pipe 20 by means of a rod *c* and a flexible connection such as a cord *d*. On a certain pressure, the float *b* adjusts the water level to the height *g*. If the pressure rises, the piston *h* in the cylinder *j* connected to the boiler by means of the connecting pipe *w* will, according to the invention, be moved outwards against the action of spring *v*, the roller *z* being then so displaced, that the connection between the float *b* and the valve *e* will, so to speak, be shortened. By this variation of the corresponding positions of the two parts, the float is adjusted to maintain a different normal water level. If the pressure falls the device will operate reversely. By means of suitable stroke stops 31 and 31^a it may be possible to prevent the water level from being adjusted beyond two limit positions. 95

Fig. 4 shows the application of the invention to an electric feed regulator, the construction of which is well known. The float *b* carries a rod *c*, on the upper end of which is fixed an iron core 2 co-operating with the coil 3. The latter device serves as a relay to open or close the feed valve. Variation of position of core 2 varies the inductance in circuit 30 which varies the position of core 2' in coil 3' correspondingly, thus opening or closing switch 31 and operating solenoid 32 to control flow of feed water through conduit 20. The coil 3 of the electromagnetic device is suspended from the piston *h* by means of the rod 4, the piston being still under the action of the boiler pressure. In this case the weight of the electro-magnet and the rod *c* may be equalized by any suitable device. It is evident that on a varying pressure the coil of the electro-magnet will be raised or lowered, the float thus being adjusted to another water level. 110

Figs. 5 and 6 show in cross section and longitudinal view respectively an embodiment of a feed regulator operating automatically with a stand pipe. The construction of this regulator is well known, it being sufficient to observe, in order to understand the device, that the supply of feed water begins at a water level which is the higher, the higher the lower mouth of the pipe 5 is situated, and vice versa. The pipe 5 is connected by means of an elastic coupling, for instance by a flexible pipe 6 and the conduit 7, to the member operating the feed regulat- 125 130

ing valve. In this case the pipe 5 may revolve about the axis 8 and is connected to the piston *i* operated by the boiler pressure through the medium of the lever 9. On a rising boiler pressure the piston will be moved downwards against the action of the spring *v*, causing a rotation of the pipe 5 upwards by means of the lever 9, for instance from the position as shown in dotted lines 10 to which the water level *g*¹¹ is adjusted, into the position as shown in full lines to which the water level *g*¹ is adjusted. On a falling pressure the rotation of the pipe 5 takes place in the opposite direction. 15 The feed valve, in this case, is controlled by a small receptacle 23 adapted to contain water and steam, and also adapted to move depending on the amount of water in the same. Movement is permitted by the **U** bends in pipes 7 and 24, which connect the receptacle with the boiler. Pipe 7 passes 20 to the upper part of receptacle 23. Pipe 24 connects the lower part of receptacle 23 with a low point in the boiler water space. 25 A weight 25 counter-balances the receptacle 23.

The operation of the regulator is as follows:

When the water level is below the level 30 of the lower mouth of pipe 5, there is no water in receptacle 23, since any water which may have been therein can then pass to the boiler through pipe 24. Weight 25 then overcomes the weight of receptacle 23 35 and the feed valve is opened.

When the level rises above the level of the lower mouth of pipe 5, receptacle 23 becomes filled with water due to condensation of steam in the same, and due to the fact 40 that there is no connection between receptacle 23 and the steam space of the boiler. The filling with water makes receptacle 23 heavy, so that its force overcomes that of weight 25 and valve *e* becomes closed. 45

In Fig. 7, a further embodiment of the invention is shown, the principle of which consists in the float or the regulating member being given an additional load, the amount of which will depend on the boiler 50 pressure. The cylinder enclosing the pressure piston should consequently be connected either to the float or to the regulating valve.

The float *b* is again connected to the said 55 valve *e* by means of a rod *c* and a cord *d*. On a rising boiler pressure the piston *h* in the cylinder *j* will effect an additional load on the float by means of the rotating lever 10, against the action of the spring *v*. This 60 additional load corresponds to a greater buoyancy to be effected by the float, that is, on a higher pressure the float has to merge deeper and the water level consequently has to rise correspondingly before the regulating 65 valve is actuated.

In case of several boilers *a* (Fig. 8) being connected to a common pump 16, the provision of a single regulating member *e* actuated by a pressure regulator will be sufficient, said regulating member being inserted in a conduit *x* from which the different boilers are fed by means of branch pipes 12, between the pump and the branch pipes. In said branch pipes, the cut-off members *r* are inserted, the same being controlled by the upper floats *m*'. Cut-off members *o*, which are normally closed and opened only when the water level has reached its minimum height, are inserted in branch pipes 15 of a conduit *y* arranged in parallel 70 to the conduit *x*. The member *e* actuated by the static steam pressure is at the same time subjected to the influence of the float *b* of one of the boilers *a*, which float controls the "normal" water level within narrow limits. 80

What I claim as new and desire to secure by Letters Patent of the United States is:—

1. Boiler feed water apparatus comprising a feed conduit, means to control flow through said conduit under normal pressure conditions solely in response to water level in the boiler, and means modifying the action of the first mentioned means for controlling the flow through said conduit under abnormal conditions solely by pressure in the boiler. 90

2. Boiler feed water apparatus comprising a feed conduit, means to control flow through said conduit, means responsive to static pressure, means to control the first-mentioned means in response to movement of the pressure responsive means, and water level control means operating to control the first-mentioned means independently of the pressure responsive means when moved by changes in water level. 100

3. Boiler feed water apparatus comprising a feed conduit, water level responsive means to control flow through said conduit, static pressure responsive means to modify the action of the water level responsive means, said water level responsive means operating the first-mentioned means independently of the static pressure responsive means at a normal value of pressure. 110

4. Boiler feed water apparatus comprising a feed conduit, a mechanism responsive to static pressure, means to cause variations in flow through said conduit in response to changes in water level and independently of the pressure responsive mechanism at a given value of pressure, and means responsive to movement of the pressure responsive mechanism modifying the action of the first mentioned means and operating to cause variations of flow through said conduit independently of values of water level. 120

5. Boiler feed water apparatus comprising a feed conduit, means to control flow through 125

5 said conduit, water level responsive means to control the first-mentioned means, static pressure responsive means to control the first-mentioned means, and interconnecting means, automatically variable in response to pressure, between the water level responsive means and the static pressure responsive means for determining their relative control of the first-mentioned means.

10 6. Boiler feed water apparatus comprising a feed conduit, control means for said conduit, water level responsive means normally operating said control means, static pressure responsive means and engageable means, normally disengaged, for operating the control means by the static pressure means under abnormal pressure conditions.

15 7. Boiler feed water apparatus comprising a conduit, mechanism to control flow through said conduit, means responsive to water level to control said mechanism and a motor responsive to static pressure modifying the action of said water level responsive means and operating to cut off the flow 20 through said conduit when the static pressure falls below a predetermined value.

25 8. Boiler feed water apparatus comprising a conduit, mechanism to control flow through said conduit, means responsive to water level to control said mechanism, a piston movable in response to static pressure and means responsive to movement of the piston modifying the action of the first-mentioned means and operating to cut off 30 the flow through said conduit when the static pressure falls below a predetermined value.

35 9. In a boiler, means to control the feed water solely in response to variations of water level at normal boiler pressure, means to control the feed water solely in response to pressure when the boiler pressure differs from normal and means to control the feed water solely in response to variations of water level at maximum and minimum values of water level.

40 10. In automatic feed water apparatus for a boiler, a conduit, means to control flow through said conduit, mechanism operated by water level to control said means at normal boiler pressure, a motor responsive to boiler pressure operating to nullify the action of said mechanism when the said boiler pressure differs by more than certain values above and below normal pressure and to regulate the supply of feed water between said 45 certain values and maximum and minimum values and water level responsive means to control the supply of feed water to the boiler by nullifying the action of the motor when the water level is above the maximum value and below the minimum value.

11. Boiler feed water apparatus comprising a conduit, a valve in said conduit, a water level responsive float adapted to operate said valve, a movable member subjected

on one side to static pressure of the boiler, a spring acting on the other side of said movable member, means whereby said movable member controls said valve at abnormal pressures, said movable member operating to 70 decrease flow through the valve when the pressure is low and increase the flow when the pressure is high.

12. Boiler feed water apparatus comprising a conduit, a valve in said conduit, a 75 water level responsive float adapted to operate said valve, a movable member subjected on one side to static pressure of the boiler, a force independent of boiler pressure acting on the other side of said movable member, means whereby said movable member controls said valve at abnormal pressures, said movable member operating to decrease 80 flow through the valve when the pressure is low and increase the flow when the pressure is high.

13. A boiler, a conduit connected therewith, a valve in said conduit, a water level responsive device to control said valve, a motor responsive to static pressure of the 90 boiler to control said valve by modifying the action of said water level responsive device, a second valve in said conduit, a high water level device to control said valve, a conduit in parallel to the first mentioned 95 conduit, a valve in the last mentioned conduit and a low water level device to control the last mentioned valve.

14. A method of controlling the water level in a steam boiler which comprises regulating the supply of feed water at certain times solely in response to water level and regardless of variations in pressure and at other times solely in response to pressure variations and regardless of variations in 105 water level.

15. A method of controlling the water level in a steam boiler which comprises regulating the supply of feed water to the boiler solely in response to changes in water 110 level so long as the boiler pressure varies between the normal pressure and a certain value above normal, regulating the supply of feed water to the boiler solely in response to pressure when the pressure is above said 115 certain value so long as a maximum value of water level has not been reached and regulating the supply of feed water solely in response to water level when the water level is above the maximum value. 120

16. A method of controlling the water level in a steam boiler which comprises regulating the supply of feed water to the boiler solely in response to changes in water level so long as the boiler pressure varies between the normal pressure and a certain value below normal, regulating the supply of feed water solely in response to pressure when the pressure is below said certain value so long as a minimum value of 125 130

water level has not been reached and regulating the supply of feed water solely in response to water level when the water is below the minimum value.

- 5 17. A method of controlling the water level in a steam boiler which comprises regulating the supply of feed water to the boiler in response to water level at normal pressure, cutting off the supply of feed water when the pressure falls below a predetermined value thus causing the water level to fall, maintaining a zero supply of feed water until a minimum value of water level is reached and supplying feed water to the
- 10 18. A method of controlling the water level in a steam boiler which comprises regulating the supply of feed water to the boiler in response to water level at normal pressure, increasing the supply of feed water when the pressure rises above a predetermined value causing the water level to
- 15 19. A method of controlling the water level in a steam boiler which comprises controlling the supply of feed water to the boiler solely in response to water level when the pressure differs by less than certain values from the normal boiler pressure and controlling the supply of feed water solely in response to changes in pressure when the pressure is above or below the said certain values.
- 20 20. A method of controlling the water level in a steam boiler which comprises regulating the supply of feed water to the boiler solely in response to changes in water level so long as the boiler pressure differs by less than certain values from the normal boiler pressure, controlling the supply of feed water to the boiler solely in response to changes of boiler pressure when the pressure is above and below the said certain values so long as the water level does not
- 25 21. A method of controlling the water level in a steam boiler which comprises regulating the supply of feed water solely in response to water level when the water level is above the maximum value and below the minimum value.
